UNITED STATES PATENT OFFICE.

CLARENCE F. STALCUP, OF SIOUX FALLS, SOUTH DAKOTA.

ROLLER JACK.

1,405,349.

Specification of Letters Patent. Patented Jan. 31, 1922.

Application filed August 19, 1920. Serial No. 404,575.

To all whom it may concern:

Be it known that I, CLARENCE F. STALCUP, a citizen of the United States, residing at Sioux Falls, in the county of Minnehaha and State of South Dakota, have invented certain new and useful Improvements in Roller-Jacks, of which the following is a specification.

- This invention relates to certain new and useful improvements in a lifting jack and more especially to a jack for automobiles the principal object being to facilitate and expedite the "jacking up" or lifting of the automobile for the purposes of repair.
- 10 A further object is to provide a jack having a long horizontal body in which the operating mechanism is located at the end opposite from the lifting end, and a still further aim of the invention is to provide 20 a lifting mechanism having an independently operable setting device carried thereby and by which the jack may be initially set or adjusted to the automobile or other body preliminary to actuating the lifting 25 mechanism.

The invention further resides in the features of construction and the arrangements and combinations of parts hereinafter described and claimed, reference being made 30 to the accompanying drawings wherein:

Figure 1 is a side view of the improved jack, a portion being broken away;

Figure 2 is a transverse section thereof through the forward end of the jack;

35 Figure 3 is a plan view of the same as viewed in Figure 1;

Figure 4 is an enlarged side elevation of the operating mechanism for the lifting device;

40 Figure 5 is a fragmentary side view of the operating end of the jack; and

Figure 6 is a transverse section thereof one line 6-6 of Figure 5.

Referring more in detail to the drawings, 45 the numeral 1 designates a pair of longitudinal side frame members pivoted at their rear ends by bolts 2 to the inner and opposite sides of the U-shaped stirrup 3 having laterally extended supports 4 in which the 50 casters 5 are mounted. Also secured at one end by these bolts 2 are the component parts of a quadrant or segmental rack 6, and pivoted to the side members 1 concentrically with the rack is a short lifting lever 7 and a long operating or controlling lever 8. The long operating lever has slidably

mounted thereon a yoke or sleeve 9 which embodies two yoke or collar portions one of which is adapted to be engaged over the upper end of the lifting lever 7, as is depicted in Figures 1 and 5. Sleeve 9 is carried on the lower end of an actuating rod 10 which is guidingly mounted on the operating lever 8 and urged in a downward direction by an encircling spring 11 while it may be retracted upwardly by means of a lever 12, pivoted to the operating lever and connected to the rod 10 by the link 13.

Obviously then, with the sleeve embracing the upper end of the lifting lever the latter 70 may be swung to any predetermined position and there held by means of a pawl 14 carried by said lifting lever and coacting with the rack 6. Pawl 14 is provided with a depressible tail 15 adapted to be engaged 75 by either branch of the lower forked terminal of the pawl releasing rod 16, the latter being slidably supported on the operating lever 8 and normally held raised by the spring 17. In the position illustrated in 80 Figure 1 branch terminal 18 is designed to engage the tail 15 and thus release the pawl, while in the position indicated in Figure 5, the branch terminal 19 is adapted to function.

The forward ends of side frame members 1 are pivoted to one corner of a triangular frame 20 which is mounted on an axle 21, supported by wheels 22, and is adapted to be swung upwardly by a pair of 90 link bars 23 connecting lever 7 with the lower most corner of said triangular frame 20. A pair of body plates 24 are secured to the side bars 1 and braced apart to form a substantial support for guiding and 95 steadyng the lift or supporting member. This comprises a long horizontal beam 25 which inclines upwardly at its forward end between the body plates 24 to provide a body supporting part 26 which rides on a 100 roller 27. A supporting head plate 28 is swiveled on the supporting part 26 and on the latter is also formed a forward and depending foot 29 designed to engage beneath the axle or hub.

In operation, the forward end of the jack 105 is moved beneath the vehicle or part to be elevated, the lift or supporting member then shifted lengthwise, by pushing on the foot piece 30 on the rearwardly projecting end 110 of the beam 25, which causes the lift head to ride up the roller until the head engages

the vehicle. Then by means of the lock pawl 31, pivoted on cradle or stirrup 3 and coacting with teeth 32 on the beam 25 the lift head is maintained in its elevated position while the operating handle is moved to raise the vehicle by swinging the triangular frame 20. This actuation lifts on the forward end of the side frame member and, consequently, the body plates 24 and head parts 26. When thus elevated to the desired height the pawl 14 is engaged with rack 6 to lock the jack in raised position. The selective engagement of sleeve 9 with lever 7 permits the operating lever 8 to assume different positions to facilitate the operation of the jack. When it is desired to release the jack either pawl 14 or 31, preferably the latter, may be disengaged by pressing thereon with the foot.

The operation is simple and positive with but little effort on the part of the operator, requiring firstly, a push with the foot on pedal 30 to set or adjust the lifting head to the object to be lifted and secondly, manipulation of the lever 8 to effect lifting of the object, and while the invention has been described in connection with vehicles its utility is not limited to this class of objects.

What is claimed is:

1. A jack comprising substantially horizontal side frame members, a transverse member formed intermediately with a stirrup in which the rear end of the frame members are mounted, wheels supporting the transverse member, a lifting member slidably and horizontally disposed between the side frame members and having its forward end upwardly inclined to provide a lifting head, means on which the inclined head rides for elevating the same, the rear end of said lifting member extending beyond the side members and formed with a series of notches, a pawl engageable in the notches of said lifting member, and means for elevating the side members.
2. A jack comprising substantially horizontal side frame members, a transverse member formed intermediately with a stirrup in which the rear end of the frame members are mounted, wheels supporting the transverse member, a lifting member slidably and horizontally disposed between the side frame members and having its forward end upwardly inclined to provide a lifting head, means on which the inclined head rides for elevating the same, means for adjusting the lifting member, and means for elevating the forward end of said side members.
3. A jack comprising substantially horizontal side frame members, a transverse member formed intermediately with a stirrup in which the rear end of the frame members are mounted, wheels supporting the transverse member, a lifting member slid-

ably and horizontally disposed between the side frame members and having its forward end upwardly inclined to provide a lifting head, means on which the inclined head rides for elevating the same, a forward wheeled axle, a triangular frame on the latter, said side members pivoted to one corner of the frame at their forward ends, and means for rocking the frame.

4. A jack comprising substantially horizontal side frame members, a transverse member formed intermediately with a stirrup in which the rear end of the frame members are mounted, wheels supporting the transverse member, a lifting member slidably and horizontally disposed between the side frame members and having its forward end upwardly inclined to provide a lifting head, means on which the inclined head rides for elevating the same, a forward wheeled axle, a triangular frame on the latter, said side members pivoted to one corner of the frame at their forward ends, a lifting lever pivotally disposed on the rear end portion of the side members, and means connecting the lever to one corner of the frame.

5. In a jack, an elongated, horizontally disposed body, lifting means arranged at one end thereof and adapted for being adjusted to the object to be lifted, means located at the opposite end of the body for adjusting said lifting means, and other means also located at said latter end of the body and operable independently of the second means for raising the body and therewith the lifting means after adjustment of the latter and while the lifting means remains in the adjusted position.

6. In a jack, an elongated, horizontally disposed body, horizontally slidable lifting means arranged on the frame and adapted for being adjusted to the object to be lifted, foot controlled means at the opposite end of the body for adjusting the lifting means and manually controlled means independently operable to bodily raise the lifting means while the latter remains in its adjusted position relative to the object.

7. In a jack, a frame, longitudinally slidably and rigidly formed lifting means mounted thereon and formed for engagement with the object to be raised, means whereby upon sliding of said means same will move longitudinally and lift the object, and means to raise the frame with said lifting means maintaining a fixed relation to the frame.

8. In a jack, a frame, lifting means longitudinally slidable on the frame and having a rigid part borne thereby and formed to engage the object to be raised, means whereby upon sliding of said lifting means the rigid part will move longitudinally therewith and engage the object, means to slide said lifting means and means to subsequently

bodily raise the lifting means while the latter maintains its said fixed relation to the object.

9. In a jack, an elongated frame, adjustable means at the front of the frame to engage the object to be lifted, means to operate and releasably hold said first means locked from and at the rear end of the frame, and means to raise the front of the frame 10 operable from the rear end thereof.

10. In a jack, a wheeled axle, an elongated frame, means to suspend the front end of the frame from the axle, a lifting member adjustable on the frame, and means to actuate the suspending means to thereby raise the front end of the frame and therewith 15 the lifting member.

11. In a jack, a wheeled axle, an elongated

frame, means to suspend the front end of the frame from the axle, a lifting member 20 adjustable on the frame, a wheeled rear member to which the rear end of the frame is pivoted, and means to actuate the suspending means to thereby raise the front end of the frame and therewith the lifting 25 member.

12. In a jack, an elongated frame, lifting means at the front end of the frame, means to adjust said lifting means operable from the rear end of the frame, and means to bodily 30 lift the front end of the frame from the rear end of the frame and with the lifting means maintaining a fixed relation to the frame.

In testimony whereof I affix my signature. 35
CLARENCE F. STALCUP.
